UNITED STATES PATENT OFFICE.

ROBERT FORD, SR., OF EARLING, IOWA.

WAGON-BRAKE.

SPECIFICATION forming part of Letters Patent No. 330,679, dated April 10, 1888.

Application filed December 10, 1887. Serial No. 257,480. (No model.)

To all whom it may concern:

Be it known that I, ROBERT FORD, Sr., a citizen of the United States, residing at Earling, in the county of Shelby and State of Iowa, have 5 invented certain new and useful Improvements in Wagon-Brakes; and I do declare the following to be a full, clear, and exact description of the invention, such as will enable others skilled in the art to which it appertains to make and to use the same.

This invention relates to wagon-brakes; and it consists in the novel construction hereinafter specified and claimed.

The invention will be fully understood from 15 the following description and claims, when taken in connection with the annexed drawings, in which—

Figure 1 is a plan view of the running gear of a wagon showing my improvements. Fig. 20 2 is a side elevation of the same with a wagon-body in position. Figs. 3, 4, 5, and 6 are detail views of parts of my improved brake apparatus.

Referring to the said drawings by letter, A 25 indicates the front wheels, and B the rear wheels, of an ordinary wagon; C C, the axles; D, the reach; E E, the hounds, and F the bolster thereof.

G represents an eccentric arranged upon the 30 front bolster. It is provided with a trunnion at each end, which passes through the stakes respectively, as shown. To provide room for the play of the trunnions, the bolster is recessed, as represented on Figs. 4 and 5, letter e. 35 On one end of trunnion a, and outside of the bolster-stake, I attach an operating-lever, K. This lever extends upward to any desired altitude above the stake of the bolster, and is provided with a releasing-dog, e, and retracting-spring f. (Represented on the drawings.) It is further provided with a ring, g, which holds the dog against its wall when desirable, and also a pawl, h, as shown.

L represents a ratchet or segment attached 45 to a bolster-stake, provided with a series of notches on its upper curved surface adapted to receive the pawl h.

It is obvious that by moving the lever K back or forth the eccentric G is rocked on its 50 trunnions in a corresponding direction. A flange (marked x x) is formed upon the upper

side of each end of the eccentric, which interposes between the body of the wagon and the stakes of the bolster and prevents said stakes from being rubbed and worn by the movements 55 of the eccentric.

M represents a perforated bar pivoted to the eccentric about midway of its length, while its opposite free end is turned down at a right angle with its body to provide means for holding the coupling-rod O. This rod O is pivoted at its rear end in the ears of a plate, i, and after being passed through an opening in the angle of bar M its front end is threaded and turned upward through one of the apertures 60 65 of said bar and made secure by means of a nut. The object of this arrangement of the bar M and rod O is to render them adjustable at will.

My brake is represented by the letter P on the drawings. It is formed of a bar of wood 70 or metal, with a rubber plate, p, at each end, and is held in position by a bent rod, S, which is secured to a parallel bar, R, that rests upon the rear hounds of a wagon and is bolted thereto, as shown. It is further connected to 75 the reach by a rod, H, as shown on Fig. 2. It is sometimes desirable to arrange the several parts in such manner that the brake cannot be operated. For this purpose I attach plates S' S² to the lower and upper sides, 80 respectively, of the rear hounds, and arrange a spring, t, thereon, as represented. Within this spring, and resting upon the pivoted lever T, is a bolt, u, adapted to enter an opening or bolt-hole in the reach. I furthermore attach 85 a cord or chain, F', to the rear end of the lever and pass it under the rear axle or under the rear bolster, and from thence upward and forward to the driver's hand. By pulling upon this cord or chain the lever T forces the bolt 90 u up into the bolt-hole in the reach, and while it is held in that position the brake is inoperative. Upon releasing the cord the spring t retracts the bolt and the brake may be operated at will.

My brake is applied by moving the lever 95 R forward. This movement rocks the eccentric in the same direction, and by means of the connections made between the eccentric and the rear wheels draw them forward against the 100 brake. In this movement the crank portions of the eccentric perform an important serv-

ice. When the vehicle is stopped on level ground, I usually apply the brake. I disengage it when the team starts. It is obvious that by so doing the front wheels will get into motion and some velocity attained before the power for moving the rear wheels reaches them. This arrangement aids materially in starting the load.

Having described my invention, what I claim
10 is—

1. The eccentric G, provided with trunnions a, in combination with a recessed bolster, F, and an operating-lever, K, said eccentric being connected with the brake, substantially as
15 shown and described.

2. In combination with the eccentric G, the pivoted and perforated bar M, coupling-rod O, and plate i, substantially as specified.

3. The plate S', lever T, spring t, bolt u, and rod or chain Y, in combination with a perforated reach, substantially as specified.

In testimony whereof I affix my signature in presence of two witnesses.

ROBERT FORD, SR.
